GRADER BLADE

Filed July 1, 1929

FIG. 1

FIG. 2

FIG. 3

INVENTOR

Charles G. Moberg.
John Harkett,
his Attorney

UNITED STATES PATENT OFFICE

CHARLES GUSTAF MOBERG, OF BROWNLEE, SASKATCHEWAN, CANADA

GRADER BLADE

Application filed July 1, 1929, Serial No. 375,282, and in Canada July 6, 1928.

This present invention relates to new and useful improvements in a grader blade and has for its primary object the provision of a grader blade structure which will assure movement of the material toward the center of the road as the material is cut away from the side of the road and the ditch or embankment along the same.

Another object of the invention resides in the provision of a grader blade of the character stated which includes an endless conveyor working longitudinally through the center of the blade proper during operation of the grader blade.

15 A further object of the invention resides in the provision of a grader blade of the character stated which is constructed in such a manner that operation of the endless conveyor within the blade proper is independent 20 of operation or functioning of the blade proper.

A still further object of the invention resides in the provision of a grader blade of the character stated which includes a simple 25 and efficient type of flexible endless conveyor mounted on the rear side of the blade proper so that the forward run thereof works longitudinally through the center of the blade proper and substantially flush therewith, guard plates being carried by the blade proper near the forward end thereof to prevent the loose material from passing through the blade.

30 A still further object of the invention resides in the provision of a grader blade of the character stated in which the endless conveyor works through the grader blade proper in such a manner that the overlapping vanes of the endless conveyor prevent the loose material from passing between the vanes and thus interfering with efficient functioning of the endless conveyor.

35 A still further object of the invention resides in the provision of a grader blade of the character stated which is highly efficient in use, comparatively inexpensive and composed of the minimum number of parts of simple and inexpensive construction and arrangement.

40 To the accomplishment of these and re-

lated objects, as will become apparent as the description proceeds, my invention resides in the construction, combination and arrangement of parts, as shall be hereinafter more fully described, illustrated in the accompanying drawings, and pointed out in the claims hereunto appended.

45 The invention will be best understood and can be more clearly described when reference is had to the drawings forming a part of this disclosure, wherein like characters indicate like parts throughout the several views.

In the drawings:

50 Figure 1 is a front elevation of the grader blade;

55 Figure 2 is a longitudinal transverse section, substantially on the plane of line 2—2 of Figure 1, looking in the direction indicated by the arrows; and

60 Figure 3 is a transverse vertical section, taken substantially on the plane of line 3—3 of Figure 1, looking in the direction indicated by the arrows.

65 Referring more in detail to the drawings, it is to be noted that the grader blade proper 6 is of conventional elongated form with its lower cutting portion 7 curved vertically or transversely and the forward lower corner 8 cut at an angle. The upper portion 9 of the grader blade proper 6 is curved outwardly at its upper edge very slightly, thus leaving the same almost straight. The main or central portion of the grader blade proper is provided with an elongated slot 10 opening 75 on the rear end thereof and extending to within a short distance of the forward end of the blade proper. On this forward end of the blade proper, a guard plate 11 is provided on its forward face and slightly flared 80 toward its free rear end. The guard plate 11 is attached to the grader blade proper 6 along the narrow forward end of the guard plate 11 and the guard plate 11 is also provided with angularly extended upper and lower edges attached to the grader blade 85 proper and extending past the forward narrow end 10a of the slot 10. The angularly extended upper and lower edges of the guard plate 11 gradually increase in width toward 90 their rear ends, thus supporting the guard 100

plate 11 at an angle with respect to the face of the grader blade proper 6.

Mounted on the rear face of the grader blade proper 6 and extending longitudinally thereof is the conveyor guide plate 12 which has its main portion spaced outwardly from the rear face of the grader blade proper 6 and extended for the greater portion of the length of the slot 10. The upper and lower longitudinal edges 13 of the plate 12 are offset from the main portion thereof and secured on the rear face of the grader blade proper 6 along the longitudinal edges of the slot 10. The forward end 14 of the plate 12 is extended at an angle with respect to the greater part of the main portion thereof and with respect to the rear face of the grader blade proper 6, thus serving as a guard for the forward end of the endless conveyor 20 which will be later described in detail. This end 14 of the plate 12 also prevents dirt or other loose material from back of the grader blade proper reaching the slot 10 unless carried thereto by the endless conveyor and thus 25 conducted by the latter to the front of the grader blade and toward the center of the road. This separation of the guard end 14 from the remainder of the main portion of the plate 12 provides an opening 15 in the forward portion of the plate 12 through which the endless conveyor operates.

Projecting from the conveyor guide plate 12, near either end thereof is a pair of bracket bearings 16 in which are carried the vertical shafts 17 for the endless conveyor. One of the shafts 17 is extended to serve as the driven shaft of the conveyor operated by any appropriate operating mechanism on the grader of which the improved grader blade is a part. On each conveyor shaft 17 is a pair of sprocket wheels 18 around which the flexible sprocket chains 19 of the conveyor operate, the anti-friction rollers 20 of the chains 19 working in the recesses of the sprocket wheels 18. Carried on the outer face of the links 21 of the conveyor chains 19 are the alternately arranged vanes 22 and 23, the latter having angular extensions 24 arranged centrally on their rear edges. The adjacent vanes 22 and 23 overlap except when passing around the sprocket wheels 18.

As the construction of the device has thus been described in detail, brief reference is now had to its use and modus operandi: The grader blade proper 6 functions in the usual manner with the portions 7 and 8 scraping the surface and cutting loose the material to be carried by the blade toward the center of the road. During this functioning of the blade proper 6, the endless conveyor also functions by rotation of the shafts 17 in the proper direction, thus causing the vanes 22 and 23 to pass through the opening 15 and then travel rearwardly in front of the plate 12 the upper and lower edges of the vanes 22

and 23 being guided between the main portion of the plate 12 and the rear face of the blade proper 6 above and below the slot 10 of the latter. As the vanes 22 and 23 pass rearwardly along the slot 10 as the forward run 70 of the conveyor, they are in overlapping relation and the angular extensions 24 of the vanes 23 serve to carry the loose material toward the rear end of the blade proper 6 and thus assure depositing of the same in the central part of the road. The conveyor also assures easier operation of the grader blade and prevents the loose material from piling on the blade proper 6 and passing over the top thereof. The guard plates 11 and 14 also serve to 80 assure proper functioning of the conveyor and prevent interference with the functioning or operation thereof by the loose material catching in and clogging the conveyor at the forward end thereof or along the 85 forward run of the conveyor. The anti-friction rollers 20 of the conveyor working on the forward face of the main part of the plate 12 serve to relieve the forward run of the conveyor of unnecessary strain and pressure 90 from the loose material being carried rearwardly by the conveyor.

From the foregoing description taken in connection with the accompanying drawings, it will be manifest that a grader blade is provided that will fulfill all the necessary requirements of such a device, but as many changes could be made in the above description and many apparently widely different embodiments of my invention may be constructed within the scope of the appended claims, without departing from the spirit or scope thereof, it is intended that all matters contained in the said accompanying specification and drawings shall be interpreted 100 as illustrative and not in a limited sense.

Having thus described my invention, what I claim as new and desire to secure by Letters Patent is:—

1. A grader blade including a blade proper 110 having an elongated central slot extended through the greater portion thereof and opening on the rear end of the blade proper; a guard member secured on said blade proper and spaced from the rear face thereof opposite the slot of said blade proper with the forward end of the guard tapered and secured firmly to the rear face of said blade proper; said guard having openings through its main central portion opposite the opposite ends of said slot in the blade proper; a small second guard plate secured on the front face of said blade proper and extending at an angle over the forward end of the slot in said blade proper; shaft bearing members projecting in pairs from the opposite ends of said first mentioned guard member; vertical shafts rotatable in said shaft supporting bracket; pairs of sprocket wheels carried on said shafts; sprocket chains operating around said sprock- 125

et wheels; and vanes carried on said sprocket chains with the alternate vanes provided with angular extensions working through said slot in the blade proper.

5 2. A grader blade including a blade proper having its lower edge curved transversely and the lower forward corners cut at an angle; the upper longitudinal edge of the blade proper being turned slightly outwardly; the main 10 central portion of the blade proper having an elongated longitudinal slot extending from a point near the forward end of the blade to the rear end thereof; shaft supporting means provided on the rear side of said blade proper adjacent the opposite ends of the slot thereof; sprocket wheels carried on said shafts; sprocket chains operating around said sprocket wheels; a guard member provided on the rear side of said blade proper with its main 15 portion opposite the main portion of the slot in said blade proper; rollers carried in said sprocket chains and operating on the forward face of said guard means and in the recess between the teeth of said sprocket wheel; overlapping vanes carried on said chains with the alternate vanes provided with outwardly directed extensions at one edge for operating through the slot in said blade proper; and oppositely directed guard means on the forward and rear faces of said blade proper projecting over the forward end of the slot thereof to prevent gathering of dirt and the like in the forward end of said slot.

20 35 In testimony whereof I hereunto affix my signature.
